his ATTORNEYS.

UNITED STATES PATENT OFFICE.

CHESTER W. CURTIS, OF GREENSBURG, PENNSYLVANIA.

ENVELOPE.

Application filed February 8, 1924. Serial No. 691,346.

This invention relates to envelopes or other containers, particularly to containers employed for the transfer of valuable articles, such, for example, as pay envelopes. The invention will be described herein with particular reference to such usage, but it will be understood that the invention is not so limited in its application being in fact capable of use for many other purposes.

10 It is the purpose of my invention to provide a container of such form that it may encompass the valuable articles to be transferred and furnish means for sealed transport of the articles from one person to another, while at the same time providing duplicate record forms, one of which is non-detachably secured to said container and hence must accompany it, and the second of which may be detached from the container 15 for the record of the person transferring the container's contents.

An especial object of my invention is the supplying of a container for currency or valuable papers, which can be formed, together 20 with duplicate receipt forms, from a single sheet of material so that any possibility of the receipts becoming separated from their proper container, either by accident, or with fraudulent intent, is removed.

30 This invention allows the duplicate record forms, together with such other matter as desired, to be printed directly upon a single sheet of material, which, by folding provides a sealable container for the valuable 35 matter to be transferred. Manifestly there can be no question of detachment of the record forms from each other, or from the container. Furthermore, the sheet or blank is so formed that it may have the receipt forms 40 printed thereon previous to folding, without requiring that the printing be matched, the seams being placed so as to be outside of the area occupied by the printed forms.

A further feature of the invention consists in so arranging the said printed forms 45 that the detachable form will lie above, and register with the non-detachable forms, so that by the use of copying composition the filling in of the one form is accomplished simultaneously with the filling in of the other.

In the preferred form of embodiment, the copying composition is applied directly to the underside of the detachable form, so that the use of separate carbon papers is rendered 50 unnecessary.

Various other features and objects of the invention will be apparent from the following description of a preferred form of embodiment thereof, having reference to the accompanying drawings in which:—

60 Figure 1 is an elevation of the unitary sheet which may be folded to provide the container and superposed receipts, as will be described.

65 Figure 2 shows the sheet of Figure 1 folded to form the container and is also an elevation.

70 Figure 3 illustrates a detail of the sheet shown in Figure 1, in fragmentary rear elevation.

75 The unitary sheet shown in Figure 1 provides a portion 5, which forms the front of the completed container and which may bear addresses, advertising, or other printed matter, for this portion remains clear and unobstructed after the sheet is folded to container form.

80 Integral with portion 5 are side flaps 7 and 11. Side flap 7 forms the back of the completed container and has printed upon it 85 that copy of the receipt for the contents of the container which is to remain with the container. This copy 8 of the receipt form is preferably spaced from the ends and one side of the flaps 7 so as not to be covered by the other flaps, as will be described. The printed forms manifestly may show such matter as may be devised. For purposes of illustration the container has been assumed to be a pay envelope and the receipt form as 90 that used for such purposes.

95 Side flap 11 is provided with an extension 14 which is preferably shorter than the flap 11, and which bears upon its face a duplicate of the receipt form 8, as indicated at 10. Upon the reverse side of extension 14 and beneath the blank spaces in the receipt form 10 is applied copying material 16 which may be any suitable composition or material, 100 many of which are well known to the reproduction and transfer arts. It will be noted from the dotted lines in Figure 1 that this copying material 16 extends only beneath the blank spaces of the receipt copy 10, thus effecting a considerable saving in cost 105 and tending to retain clean records since smudging by careless handling is prevented.

110 Portion 5 has also integral therewith a top flap 20 and a bottom flap 22. These flaps, as well as flap 11, are preferably lined

with gum, or mucilage, so that by folding flap 7 upon line 9, flap 11 upon line 12, and flap 22 upon line 23, and sealing these flaps, a container in envelope form is produced as shown in Figure 2.

Folding as has just been described, brings the extension 14 over and above the flap 7 in such manner that receipt form 10 lies directly over form 8, the blank spaces of the 10 two registering one with the other. Thus it will be seen that from a single piece a container bearing a non-detachable receipt form 8, and a duplicate form 10, is produced. It will also be evident that money placed within 15 in the container may be sealed in by folding down and sealing flap 20.

Extension 14, bearing receipt form 10, joins to the flap 11 upon line 15, and may be torn off upon that line when it is desired 20 to separate the receipts, (as upon delivery of the container). The sheet material is preferably perforated upon line 15 to aid detachment.

To make clear the improvements accomplished 25 in a specific case, use in paying employees' wages will be described.

The user simply marks the employee's name, hours employed, sum enclosed, and other pertinent data in the spaces provided 30 on form 10, then inserts the employee's wages in the container and seals the flap 20. Through the means of the copying material 16, the data is duplicated upon the receipt form 8. The container is then ready 35 for the pay box and manifestly the sum within the container cannot be tampered with, without opening the same, which would leave such trace as to be readily detected. Nor can either of the receipts be 40 detached from the proper container without leaving evidence of such detachment. Confusion of receipts is, therefore, practically impossible.

Upon receiving the envelope, the employee 45 simply signs his name in the proper space on receipt form 10, this act transferring (through material 16) a duplicate copy to the container form 8. The paymaster then tears off extension 14 and hands the employee 50 the envelope which bears upon its face a duplicate in receipt form 8, of the receipt 10 which the employer retains. Thus both employee and employer are afforded a record which tallies correctly and by which 55 either may check any discrepancies with the absolute assurance that the other's record is the same as his own. All chance for attempts, or accusations, of fraud are removed.

It will be evident that the foregoing use 60 is but one of many possible ones, that the form of container employed is but for purpose of illustration and that by employing many other forms of container which can be formed from a single sheet, other articles varying in bulk, and in form, may be han-

dled with safety and with the assurance of an accurate record at a minimum of labor and expense. Such changes in form of the whole and of its parts may manifestly be made within the spirit of my invention and 70 the scope of the appended claims.

What I claim is:—

1. In an envelope, a body portion bearing a receipt form upon its face and having a detachable flap integral with said body portion, said flap and the body portion therebeneath bearing registering duplicate forms provided with spaces wherein written record may be made, and transfer means applied to the under surface of the flap for 80 duplicating said written record on the form of the body portion. 75

2. A one-piece record and receipt envelope comprising a front panel, a back panel, a side flap folded upon the back panel and adhesively secured to one longitudinal margin thereof, a bottom flap folded over the back panel and adhesively secured thereto, a top flap foldable over the back panel and over the upper end of the side flap for sealing 90 the envelope, and an extension on said side flap overlying the back panel, said extension and back panel having duplicate registered printed forms thereon, the extension being connected to the side flap along a weakened line of detachment, and being shorter than the side flap to escape the top sealing flap and remain free thereof, said extension being coated with a transfer medium on the side thereof next to the back panel to reproduce on the back panel matter written on the extension. 95

3. In an envelope, a blank having end and side flaps, one of said side flaps bearing upon its surface a record form, the second of said side flaps being provided with an extension integral therewith and detachable therefrom, said extension bearing upon its surface a duplicate of the record form upon the first said flap and being sufficiently shorter than the flap of which it forms a part to permit the end flaps to be sealed over said flap without obstructing said detachable portion. 105

4. In an envelope, a blank having end and side flaps, one of said side flaps being provided with an extension integral therewith and detachable therefrom, said extension being sufficiently shorter than the flap of which it forms a part, to permit the end flaps to be sealed over said flap without obstructing said detachable portion. 110

5. A device of the character described which comprises a container provided with a detachable flap lying upon a surface thereof, duplicate receipt forms upon said flap and upon the container surface therebeneath, and means upon said flap whereby impressions made upon it are duplicated upon the container surface. 125

6. A device of the character described which comprises a container formed from a single sheet and providing a body portion and a flap lying over and upon said body portion, said flap and the aforesaid body portion bearing duplicate receipt forms, and means upon the underside of said flap, whereby writing upon the flap is automatically duplicated upon the exterior of said body.
7. An envelope comprising a detachable flap provided with a form for receiving a record, the body of said envelope being provided with a form corresponding to said first-mentioned form on said flap, said flap on its under side being provided with trans-
- fer material, so that writing in the form on said flap will be transferred to the form on said body.
8. In an envelope, a body portion having a detachable flap integral therewith, said flap and the body portion bearing registering duplicate forms provided with spaces wherein written record may be made, and transfer means applied only to the portions of the under surface of the flap which are superposed upon said written record spaces of the form on the body portion.

In testimony whereof I have affixed my signature to this specification.

CHESTER W. CURTIS.
